7 Claims. (Cl. 179—171)

1

This invention relates to microwave amplifiers, and particularly to amplifiers for electric oscillations in the range of the shorter decimeter and centimeter waves.

Prior microwave amplifiers have been of the traveling-wave tube type or of the velocity-modulated beam or "Klystron" type. The load must be adjusted to the output characteristic of a traveling-wave tube within definite limits to avoid a disturbing back-coupling between the amplifier output and input, and variations in the load impedance may seriously affect the efficiency or rate of amplification. In amplifiers operating on the Klystron principle, an electron beam is velocity modulated in a resonator or rhumbatron by the oscillations to be amplified and, at a certain distance beyond the resonator where the electrons are more or less bunched, the beam energizes a second resonator from which the amplified oscillations may be withdrawn. The bunching of the electrons may be improved by locating additional resonators of the same or similar type between the input and output resonators, the additional resonators being energized by the electron beam to oscillate freely at natural frequencies which satisfy certain conditions. Each resonator can impose but one bunching or amplifying action upon the beam, and the resonators must be spaced apart by a sufficient distance to develop the focussing of the beam.

Objects of the invention are to provide microwave amplifiers in which an electron beam travels along a plurality of resonators, each resonator interacting a plurality of times with the beam, the first resonator being energized by the oscillations to be amplified, and the amplified energy being abstracted from the last resonator. Objects are to provide microwave amplifiers of the character stated in which the resonators have natural frequencies of oscillation equal at least approximately to the frequency of the microwaves to be amplified, each resonator comprising a metal box having one wall divided by a zigzag slot into a plurality of pairs of interleaved segments supported in alternation from opposite side walls of the box; and in which the elements cooperating with a row of resonators include a guide electrode extending along and facing the slotted faces of the resonators, a cathode and a collecting electrode adjacent the input end and output end, respectively, of the resonators for establishing an electron beam in the space between the resonators and the guide electrode, and a magnet or electromagnet for establishing a unidirectional magnetic field transverse to the

2

electron beam and parallel to the resonator segments.

These and other objects and the advantages of the invention will be apparent from the following specification when taken with the accompanying drawing, in which:

Fig. 1 is a perspective view of one of the resonator elements of an amplifier embodying the invention;

Fig. 2 is a longitudinal section through the same;

Fig. 2a is a curve sheet showing the magnitude of the high-frequency voltage between adjacent resonator segments as a function of the position of the segments in the resonator;

Fig. 3 is a perspective view, with some parts broken away, of a microwave amplifier embodying the invention, the magnet being omitted for clarity of illustration;

Fig. 4 is an end view of the amplifier;

Fig. 5 is an end elevation of another embodiment of the invention in which the electron beam travels along a curved path;

Fig. 6 is a fragmentary perspective view of a high inductance type of guide electrode;

Fig. 7 is a fragmentary perspective view, partly in section, of an alternative coupling to an input or output resonator; and

Fig. 8 is a schematic perspective of a pair of coupled resonators for use in a wide band amplifier.

As shown in Figs. 1 and 2, the resonator elements of the amplifier are elongated boxes R of a nonmagnetic metal and of rectangular cross-section with one long wall divided by a zigzag slot A into a plurality of pairs of interleaved segments S₁, S₂ of identical rectangular form, the segments being supported in alternation from opposite side walls of the resonator. Except for the end resonators of a plurality or series incorporated in an amplifier, which end elements must be provided with openings for the introduction of input and output coupling elements, the zigzag slot A constitutes the only opening in the walls of the resonator elements.

The direction of the magnetic alternating field established within a resonator of the amplifier is indicated in Fig. 2 by the double-ended arrow H, and the variation in the magnitude of the high-frequency potential between adjacent resonator segments with their position in the resonator is shown graphically by curve U of Fig. 2a.

In a constructional embodiment of the invention, as shown in Fig. 3, a series of three resonators R₁, R₂ and R₃ are spaced from each other

by small gaps F_1 , F_2 and secured to a rail or strap G of nonmagnetic material which supports them within an evacuated envelope D . The segmental walls of the several resonators face and are parallel to a guide electrode L of strap or band form which extends along and projects somewhat beyond the ends of the resonator assembly. A cathode K is arranged transversely of the guide electrode L , and in part within a semicylindrical depression of the electrode L , at substantially the outer end of the resonator R_1 into which extends an input loop I with leads P_1 for connection to the source of microwaves to be amplified. The cathode K and a collector electrode C at the opposite end of the tube establish an electron beam in the interspace between the segmental faces of resonators and the guide electrode L . One or more additional cathodes K_1 may be provided along the guide electrode L to increase the magnitude of the beam current towards the output end of the resonator series in accordance with the increase in oscillation energy. A plurality of cathodes is particularly advantageous when the amplifier is to deliver considerable power. The terminal resonator R_3 of the series is provided with a coupling element, not shown, having leads P_2 for connection to the antenna or other load device upon which the amplified microwave energy is to be impressed.

A unidirectional magnetic field is developed in the space between the resonator segments and the guide electrode, and in the direction indicated by the arrows N of Fig. 3, by a permanent magnet or other electromagnetic system M , Fig. 4.

The method of operation of an amplifying tube of the construction so far described is as follows. The collecting electrode C and the resonators are maintained at a positive direct current potential with respect to the cathode K by any appropriate current source, not shown, and the guide electrode L is maintained at the same, or approximately the same, potential as the cathode. These relative potentials will of course result in an electron beam to the collector electrode C when the cathode K is heated to liberate electrons, and the electrons move on cycloidal orbits in view of the magnetic field in the direction N . So long as the input resonator R_1 is not energized by a high frequency input injected by loop I , the electron beam will be substantially homogeneous or of the same density at all transverse cross-sections.

Upon energizing the input resonator R_1 by impressing the oscillations to be amplified across the input leads P_1 , the alternating magnetic field H established within the resonator develops an alternating potential difference U between adjacent segments S_1 and S_2 of the resonator; all segments S_1 being instantaneously of the polarity opposite that of the group of segments S_2 , and the polarity of the segments reversing at the frequency of the oscillations to be amplified. The alternating potentials thus developed on the resonator segments exert a focussing effect upon the electron beam and the electrons leave the range of the resonator R_1 in packets or bunches which succeed each other at the frequency of the oscillations to be amplified. The bunching of the electrons is very marked, particularly in the vicinity of the exit end of the resonator, as the initial bunching effected by the first resonator segments interacts with the later segments to increase the excitation of the resonator and the magnitude of the potential differences between adjacent resonator segments as initially established by the microwave energy introduced into

the resonator at the loop I . The repeated interactions between the electron beam and the resonator segments distinguish the invention from the known amplifiers in which each resonator imposes only a single bunching action upon the electron beam. It is to be noted that the length, and hence the number of segments, of a resonator can not be increased indefinitely as the resonator will break into self-oscillation if too many reactive couplings are provided.

The bunched electron stream leaving the range of the first resonator R_1 reacts with the initial segments of the next resonator R_2 to energize the same, and is further focussed and more compactly bunched by the interaction of the resonator segments and the electron beam. Similarly, the resonator R_3 is energized by the bunched electron stream leaving the second resonator, and the amplified oscillations are abstracted from the output resonator by a loop and the leads P_2 .

A special advantage of the described amplifier is the absence of a reactive coupling between the output and input resonators. The amplifier is therefore stable in operation and is not materially affected by wide variations in the frequency and/or impedance of the load into which it works. When connected to a transmitting antenna, for example, its stability is not affected by hoarfrost or ice which collects on the antenna and changes its electrical characteristics. The amplifier is therefore particularly suitable for the amplification of frequency modulated oscillations where it is difficult to maintain a close matching of the amplifier output characteristics and the load characteristics over the frequency range of the transmitted signals.

The linear arrangement of the resonator series and guide electrode is not essential for operation in accordance with the invention and it may be more convenient, for manufacturing or other reasons, to employ a cylindrical construction such as shown in Fig. 5. Except that the several elements are arcuate in place of linear, they correspond exactly to elements shown in Fig. 3 and are identified by primed reference characters but will not be described in detail. The opposed surfaces of the resonator elements and the guide electrode G' are coaxial to provide a beam path of constant cross-section from end to end thereof.

The band type of guide electrode shown in Figs. 3 and 5 usually affords only a negligible back-coupling of the output resonator to the input resonator and even this back-coupling is suppressed by a guide electrode L_1 in the form of a flattened spiral winding of wire, with slightly spaced adjacent turns, Fig. 6, which has a very high impedance at the frequency of the oscillations to be amplified.

In place of the loop couplings to and from the resonators, a pair of input or output leads P may be connected directly to two segments S_1 and S_2 of a resonator, as shown in Fig. 7.

The several resonators of Figs. 3 and 5 are designed and constructed to resonate at substantially the frequency of the oscillations to be amplified. When the amplifier is to operate over a relatively wide range of frequencies, each resonator element of the amplifier comprises two resonators R' and R'' in series in the row of resonator elements and coupled electrically or magnetically as indicated by a jumper J , Fig. 8; the resonators of each pair being tuned to somewhat different frequencies, for example to fre-

5

quencies ($f+x$) and ($f-x$) as indicated by such notations on the respective resonators.

It is to be understood that the invention is not limited to the particular embodiments herein shown and described as various modifications thereof fall within the spirit and scope of the invention as set forth in the following claims.

I claim:

1. A microwave amplifier comprising an evacuated envelope to be located in a unidirectional magnetic field, cathode means and a collector electrode within said envelope and spaced from each other to develop an electron beam, a plurality of resonator elements extending in spaced decoupled sequence along the path of the electron beam, each resonator element comprising an elongated metal box having a natural frequency of oscillation at least approximately coinciding with a frequency of the microwave oscillations to be amplified and having the wall thereof opposed to the electron beam divided by a zigzag slot into a plurality of pairs of interleaved segments which extend transversely to the path of the electron beam, input and output coupling means extending into the resonator elements respectively most remote from and closest to said collector electrode, and a guide electrode extending along the path of the electron beam at the side thereof opposite said resonator elements; said amplifier being adapted to be energized by maintaining said collector electrode and resonator elements at positive potentials with respect to said cathode means and said guide electrode, and establishing a unidirectional magnetic field through the interspace

6

between said resonator elements and said guide electrode parallel to the resonator element segments.

2. A microwave amplifier as recited in claim 1, wherein the guide electrode and the surface defined by the opposed segmental walls of the resonator elements are substantially linear and parallel.

3. A microwave amplifier as recited in claim 1, wherein the guide electrode and the surface defined by the opposed segmental walls of the resonator elements are cylindrical and substantially coaxial.

4. A microwave amplifier as recited in claim 1, wherein said guide electrode is of strip form.

5. A microwave amplifier as recited in claim 1, wherein said guide electrode comprises a flattened spiral winding of spaced turns of wire.

6. A microwave amplifier as recited in claim 1, wherein said cathode means comprises a plurality of spaced cathodes, one cathode being located adjacent the outer end of the resonator element most remote from said collector electrode.

7. A microwave amplifier as recited in claim 1, and for operation over a band of frequencies, wherein each resonator element comprises a pair of coupled resonators in series arrangement along the path of the electron beam, the resonators of each pair having natural frequencies of oscillation respectively above and below the mean frequency of said band of frequencies.
